UNITED STATES PATENT OFFICE.

PHILLIP J. COATES, OF MACON, GEORGIA.

CUSHIONED HORSESHOE.

SPECIFICATION forming part of Letters Patent No. 705,908, dated July 29, 1902.

Application filed February 13, 1902. Serial No. 93,916. (No model.)

To all whom it may concern:

Be it known that I, PHILLIP J. COATES, a citizen of the United States, residing at Macon, in the county of Bibb and State of Georgia, 5 have invented certain new and useful Improvements in Cushioned Horseshoes; and I do declare the following to be a full, clear, and exact description of the invention, such as will enable others skilled in the art to which it applies to make and use the same.

This invention relates to horseshoes, and particularly to that class of horseshoes of the cushioned type in which solid rubber is employed in the construction, thereby rendering the shoe easy to the foot, noiseless, and antislipping.

The object of the present invention is to provide a cushioned horseshoe in which a metallic reinforcing and nailing plate is contained within a rubber body and is adapted when the body is worn out to be removed therefrom and inserted within another body, thus making the plate available for use for an indefinite period.

With this and other objects in view the invention consists of certain novel features of construction, combination, and arrangement of parts, as will be hereinafter more fully described, and particularly pointed out in the appended claim.

In the accompanying drawings, Figure 1 is a top plan view of a horseshoe embodying my invention, showing the covering-flaps turned back to expose the nailing and reinforcing plate. Fig. 2 is a side elevation of the shoe, a portion being broken away to show the plate; and Fig. 3 is a cross-section through the shoe with the flaps closed.

Referring now more particularly to the drawings, the numeral 1 represents the body of the shoe, formed of rubber cast or molded into shape and vulcanized to the desired degree of hardness, the rubber having, however, sufficient elasticity to afford a proper cushioning action. This body is provided with a continuous chamber 2 to receive a horseshoe-shaped nailing and reinforcing plate 3, having nail-holes 4 coinciding with corresponding holes 5 in the base of said body.

This plate gives the body the necessary rigidity to withstand rough usage and forms a rigid backing to adapt the shoe to be securely nailed to the hoof. The chamber 2 is closed at top by overlapping flaps 6 and 7, which

when closed confine and conceal the plate 3. 55 These flaps are formed with or suitably secured to the inner and outer edges of the body and when the shoe is attached to the hoof are held closed by the passage of the nails through them. When the body becomes 60 worn out and the shoe is detached from the hoof, the plate 3 may be removed by opening the flaps and inserted into another body for further use.

It will thus be seen that a simple and effective form of shoe is provided and that by its use the necessary cushioning action is secured, while the shoe is adapted to be fastened securely to the hoof and to prevent slipping on slippery roads and streets; also, 70 that by the construction described the plate 3 may be used indefinitely, thereby obviating the necessity of forming the plate in the shoe or providing one for each shoe, so that a considerable saving in the cost of shoeing will be 75 effected in the course of time, especially by those maintaining large stables.

I may employ thickened or auxiliary rubber heels or a frog-bar whenever it may be found necessary or desirable.

From the foregoing description, taken in connection with the accompanying drawings, the construction, mode of operation, and advantages of the invention will be readily understood without requiring a more extended 85 explanation.

Various changes in the form, proportion, and the minor details of construction may be made within the scope of the invention without departing from the spirit or sacrificing 90 any of the advantages thereof.

Having thus described my invention, what I claim, and desire to secure by Letters Patent, is—

A horseshoe comprising a rubber body having a chamber open at top, flaps for closing said chamber, and a nailing and reinforcing plate removably seated in said chamber and concealed by said flaps, substantially as set forth.

In testimony whereof I have hereunto set my hand in presence of two subscribing witnesses.

PHILLIP J. COATES.
